WINDOW CONSTRUCTION

Ulrich Anderson, Madison, Wis.

Application December 1, 1931. Serial No. 578,357

9 Claims. (Cl. 20—45)

This invention relates to windows and more particularly to sash guides designed to permit the sashes of the window to be swung inwardly to facilitate cleaning thereof.

In its broad aspects the invention contemplates the provision of swingable sash guides pivotally secured to the window casing and to each other in such a manner that the upper and lower sashes, as well as their guides, may be swung inwardly at the same time.

10 The invention also includes an arrangement of the pivotal connections between the guides such that in their normally closed position the guides are substantially self-locked with respect to each other and to the casing.

15 A further improvement resides in the form of sash weight suspension within the casing and adjustable take-off rollers adapted to be swung into effective position when it is desired to swing the sashes inwardly.

20 Other objects of the invention will be apparent from the following description thereof taken in connection with the accompanying drawings, in which:—

25 Fig. 1 is a side sectional elevation of the window illustrating the relative positions of the constituent elements when the window is fully closed;

30 Fig. 2 is a sectional view similar to Fig. 1, but showing the sashes and guides swung inwardly to open position;

Fig. 3 is a sectional view similar to Fig. 1, the sashes being swung to partially open position for ventilation;

35 Fig. 4 is a front sectional elevation taken on line 4—4 of Fig. 2;

Fig. 5 is an enlarged view of the upper portion of the sash guide and pulleys for the weight cords;

40 Fig. 6 is a perspective of the guides and connection therebetween;

Fig. 7 is a side elevation of the weight suspension;

Fig. 8 is a partial detail view of the sash guide 45 lock;

Fig. 9 is a sectional view taken on line 9—9 of Fig. 8;

Fig. 10 is a sectional view taken on line 10—10 of Fig. 8; and

50 Fig. 11 is a perspective of the swingable support for the take-off pulleys.

Referring to the drawings, the window comprises the usual casing 20 and sliding sashes 21, 22. Interposed between the sashes and the casing, at each side thereof, are metallic plates

23 and hinged guide frames 24, 25, the latter being pivoted to swing about horizontal axes near the bottom and middle of the window respectively. Each of the upper guide frames is pivotally secured to plates 23 by means of beveled 60 discs 26 welded to the frames and cooperating with undercut openings 27 in the plates. The lower guide frames are similarly pivoted to the plates by discs 28 cooperating with openings 29.

It will be noted that the pivots are in line 65 respectively with the vertical positions of the upper and lower sashes.

The guide frames are each provided with a rear flange 31 and channel members or guide strips 32 for guiding the sashes in their normal 70 vertical sliding movement. The lower guide frame is somewhat wider than the upper frame, but when the frames are swung into vertical alignment, flanges 31 and channels 32 are also in alignment to form a continuous guide groove 75 for the sashes. The guide frames are cut away at 33 and 34 so that they may be swung into closed position without interference. Furthermore, the upper end of the lower guide is formed to be complementary with the cut-away portion 80 of the upper frame, thus forming, when the frames are vertically aligned, practically a continuous frame from top to bottom.

The frames are connected at their top ends by connecting members 35, the connection being 85 made by means of discs 36, 37, welded to the connecting members and fitting in undercut openings 38 in the frames. The connecting member also is provided with a channel 32 forming one of the guides for the lower sash. 90 It will be seen that the connecting member is forked at its upper end 39 for connection with a projection 41 on the upper guide frame. When the sashes are swung inwardly, their guides remain in substantially parallel relation since their 95 pivot points remain fixed and their upper ends are constrained to move together.

As will be seen from Fig. 1, pivot disc 36 is offset with respect to discs 26, 37, so that, as the sash guides are swung past the center line 100 of fulcrum points 26, 37, the abutting ends of the guide frame tend to snap either into fully closed position or partly open position. In this respect the frames are practically self-locking.

A semi-circular projection 40 on the upper 105 sash guide cooperates with a similarly shaped recess 40' in plate 23 properly to align the guides.

The upper end of guide frame 24 is spaced 110 from the top of the window casing, this space

being filled by a swingable support 42 for take-off pulleys 43, which are normally disposed in the counter-weight space of the casing. Short channel members 44 on this support form a continuation of guide channels 32. Each pulley support is pivoted at 45 and normally lies flat against plate 23, being locked in its normal position by a pivoted latch member 46 having a flange 47 thereon designed to cooperate with notch 48 on a pin 49 secured to the plate. The support is swung out to position pulleys 43 in the path of weight ropes 51, as shown in Fig. 4, when the sash guides are to be lowered. In order to free the support for swinging movement, latch 46 is turned until flange 47 disengages notch 48. After the pulleys have been positioned, the latch engages a second notch 52 to hold the support in this position. The support may, of course, be swung up to a horizontal position better to facilitate stringing of the weight cords.

The method of counter-balancing the sashes is illustrated in Fig. 2. A single rope or flexible cable 51 on each side of the window is connected at each end to one of the sashes. Counter-weights 53 are suspended from a bracket 54 carrying pulleys 55, 56. Pulleys 57, 58 are mounted in bracket 59, while still another pulley 61 is supported by a chain 62 hung from bracket 59. The weight rope passes around pulleys 57, 56, 61, 55, 58, in the order named, the arrangement being such that the guide frames may be swung down to a substantially horizontal position due to the relatively long weight cord and the short travel of the weight as compared with that of the sashes.

In Fig. 4 it will be noted that suitable weather stripping 63 is mounted on each side of the sashes, the stripping preferably being felt or other flexible material fitting within brackets 64 and being pressed into channels 32 by bowed spring members 65. This insures weather-proof windows and prevents rattling of the sashes in their guides.

When the guide frames are in fully closed position, that is, in vertical alignment, they are locked flush against plate 23 by the latch device shown in Figs. 8, 9, and 10. The abutting ends 69, 60' of the frames are inclined downwardly in the direction of closing so that the upper frame cannot be displaced without first moving the lower frames. The latch 66 is provided with a beveled semi-circular disc 67 cooperating with an undercut semi-circular recess 68 in plate 23 when the latch is in the position indicated in Fig. 8, thus locking the lower frame to plate 23 and preventing any relative movement of the sash guides. When it is desired to unlock the frames, the latch is rotated 180°, the semi-circular disc being removed from recess 68, whereupon the frames may be swung on their fulcras.

Fig. 3 illustrates the window in a partially open position for ventilating purposes. It is apparent that the frames cannot be swung inward further while the upper sash is in its topmost position, nor can the lower frame be moved toward closed position while latch 66 is in the position shown, disc 67 being in abutting relation to the edge of plate 23. It is also apparent that the lower sash cannot be raised due to interference with the channel guide 32 on connecting member 35. While the window is thus opened for ventilation, it is locked against movement in either direction so that wind or manipu-

lation from the exterior of the building cannot open or close the window further.

The casing is, of course, provided with a suitable opening 69 to permit access to the counter-weights. A closure plate 71 covers this opening, and when the sash guides are in their normal position, the opening and plate are covered.

From the foregoing description it is obvious that the sashes may be raised and lowered in the ordinary way, but when it is desired to wash or repair the windows, the guide frames and sashes may be swung inwardly simultaneously and made easily accessible. It is furthermore apparent that the guide frames may be spaced a slight distance from each other for ventilating purposes and effectively locked in this position.

While a detailed description of a preferred embodiment of the invention has been incorporated herein, it is to be understood that the invention is not to be limited to the exact arrangement of the constituent elements illustrated, but that the invention is susceptible of modification.

What is claimed is:—

1. In combination with a window casing, upper and lower sashes; upper and lower guide frames for the sashes, said sashes being slidable in said frames, each of said frames being pivoted at its lower end to said casing; and a connector pivotally secured to the upper ends of said frames whereby the frames are swung in parallel relation.

2. In combination with a window casing, upper and lower sashes; upper and lower guide frames for the sashes, said sashes being slidable in said frames, each of said frames being pivoted at its lower end to said casing; and a connecting member pivotally secured at each end to the upper ends of the upper and lower frames respectively, the connection of the lower frame with the connecting member being offset with respect to the line passing through the connection of the lower frame with the casing and the connection of the connecting member with the upper frame when the frames are in vertical alignment.

3. In combination with a window casing, upper and lower sashes; upper and lower guide frames for the sashes, said sashes being slidable in said frames, each of said frames being pivoted at its lower end to said casing; a connecting member pivotally secured at each end to the upper ends of the upper and lower frames respectively, said lower and upper frames being in abutting relation when the frames are in vertical alignment, the abutting edges of the frames being inclined to the sides thereof; and means for locking one of the frames to the window casing.

4. In combination with a window casing, upper and lower sashes; upper and lower guide frames for the sashes, said sashes being slidable in said frames, each of said frames being pivoted at its lower end to said casing; a connecting member pivotally secured at each end to the upper ends of the upper and lower frames respectively, said lower and upper frames being in abutting relation when the frames are in vertical alignment, the abutting edges of the frames being inclined to the sides thereof; and a latch member on one of said frames cooperating with the window casing when the frames are in vertical alignment to lock the frames in closed position.

- tion, said latch member being adapted to abut the longitudinal edge of the casing when the window is partially open to prevent closing of the window.
- 5 5. In combination with a window casing, upper and lower sashes; upper and lower guide frames for the sashes, said sashes being slid-able in said frames, each of said frames being pivoted at its lower end to said casing; 80
10 a connecting member pivotally secured at each end to the upper ends of the upper and lower frames respectively; guide strips on said frames; a member secured to the side of the casing above said upper frame and having guide strips thereon, said member being incapable of swinging in the same direction as said frames, said frames being locked against swinging movement until the upper sash has been lowered below said member.
- 15 6. In combination with a window casing, upper and lower sashes; upper and lower guide frames for the sashes, said sashes being slid-able in said frames, each of said frames being pivoted at its lower end to said casing; a counter- 85
20 weight for said sashes; a flexible cable connecting said weight to said sashes; a support member pivotally secured to the side of the casing above said upper frame; and take-off rollers mounted on said support member over which 90
25 said cable is adapted to pass when the frames are swung to open position.
- 25 7. In combination with a window casing, upper and lower sashes; upper and lower guide frames for the sashes, said sashes being slid-able in said frames, each of said frames being pivoted 95
30 to open position.
